DESIGN FOR A DRAFT DIVERTER FOR DOMESTIC WATER HEATERS OR THE LIKE

Clarence H. Morrow, Shaker Heights, Ohio, assignor to The Hotstream Heater Company,
Cleveland, Ohio, a corporation of Ohio

Application October 6, 1938, Serial No. 80,292

Term of patent 14 years

To all whom it may concern:

Be it known that I, Clarence H. Morrow, a citizen of the United States and a resident of Shaker Heights, in the county of Cuyahoga and State of Ohio, have invented a new, original, and ornamental Design for a Draft Diverter for Domestic Water Heaters or the like, of which the following is a specification, reference being had to the accompanying drawing, forming a part thereof.

In said drawing, Fig. 1 is a side elevational view of a draft diverter for domestic water heaters or the like, showing my new design, the color of the band encircling the enlarged part of said draft diverter being of contrasting character relative to that of the other portions of such draft diverter; and Fig. 2 is a top plan view thereof.

I claim:

The ornamental design for a draft diverter for domestic water heaters or the like, as shown and described.

CLARENCE H. MORROW.
